Norman J. Whitaker

Uttosmer;

UNITED STATES PATENT OFFICE.

GEORGE J. PAULY, OF FRACKVILLE, PENNSYLVANIA.

SIGNAL.

1,215,979.

Specification of Letters Patent. Patented Feb. 13, 1917.

Application filed May 31, 1916. Serial No. 100,960.

To all whom it may concern:

Be it known that I, GEORGE J. PAULY, a citizen of the United States, and resident of Frackville, in the county of Schuylkill, 5 State of Pennsylvania, have invented certain new and useful Improvements in Signals, of which the following is a specification.

My invention relates to an audible signaling apparatus to be used in mines. More 10 specifically the invention comprehends an apparatus to be used in connection with lifts, cars, buckets, etc., that are used for lowering and hoisting miners into and out 15 of the mine.

The main object of the present invention is to provide a signaling apparatus of the above mentioned character which may be operated from the mine car, etc., to warn 20 the engineer who is lowering the same that the persons in the car, etc., are in danger.

A further object of the invention is to provide a cable which is used for lowering and raising conveyances of the above mentioned type having electricity conductors 25 embedded therein that are connected with the audible signal.

Another object of this invention is to utilize the cable as an insulator for the electricity conductors as well as to raise and 30 lower the conveyances.

A still further object of the invention is to provide a novel mounting for the audible signal and the electric batteries whereby 35 they can be easily reached, and where the signal may be easily heard by the engineer.

An additional object of the invention is to provide a signaling apparatus of the above mentioned character which can be applied 40 to any mine conveyance, that consists of few parts, is inexpensive to manufacture, and which may be placed on the market at a comparatively low cost.

With the above and other objects in view 45 which will become apparent from the following specification taken in connection with the accompanying drawing, the invention consists of the constructions, combinations and arrangement of parts which will be 50 hereinafter set forth in detail.

On the drawings,

Figure 1 is a longitudinal sectional view through a drum having my invention applied thereto.

55 Fig. 2 is a view looking down on the top

of the drum, the door being shown in dotted lines in an open position.

Fig. 3 is a side view of the drum and showing diagrammatically the electricity conductors connected with the circuit closer. 60

Fig. 4 is a view of the mine car and track upon which it travels; and

Fig. 5 is a view of a portion of the cable showing the electricity conductors projecting from one end thereof. 65

The numeral 5 designates supporting bearings in which is mounted a shaft 6. Rotatably mounted upon this shaft is a drum 7 for raising and lowering the mine conveyance 8 that may be of any preferred 70 type, but is shown in this instance as a car. This drum 7 is rotated by any desirable means.

A conventional track-way is shown at 9 which extends from the surface of the mine 75 to the bottom thereof and upon which the car 8 travels.

Connected to the car 8 is a cable 10 which is also secured to the drum 7 and is adapted to be wound therearound. Arranged in this 80 cable 10 are wires or electricity conductors 11 which are connected with any desirable circuit closer 12 which is shown in this instance as a push button and is mounted in a casing 13 on the car 8. 85

Formed in one side of the drum 5 is an opening 14 and normally closing this opening is a door 15 which is supported by the hinges 17. A keeper 18 is carried by the door 15 and normally retains the same in 90 closed position.

One end of the cable 10 is extended through an opening in the drum 7 and seated in a longitudinal recess 19.

Supported on the door 15 is a battery 20 95 which is in circuit with the wires 11 of the cable 10. Also supported upon the door 15 is an audible signal 21 which may be a bell, buzzer or the like. This signal is also in circuit with the wires 11 and the source of 100 electrical energy 20. It will be seen that by mounting the battery and signal in the above manner, they are not subjected to the weather and that by simply opening the door 15, access may be had to them without 105 any difficulty.

From the foregoing disclosure, it is obvious that by simply pressing the push button 12, the engineer is warned that the miners in the car 8 are in danger. 110

While I have disclosed the preferred embodiment of my invention, I desire it understood that the same is susceptible of various modifications and alterations that 5 may fairly fall within the scope of the appended claims.

What is claimed is:

1. In a signal, a drum having an opening therein, a door closing the opening, a signal

arranged in the interior of the drum, and 10 means for operating the signal.

2. In a signal, a drum having an opening therein, a door closing the opening, a source of electrical energy mounted upon the door, an electrical signal also mounted upon the 15 door and in circuit with the electrical energy.

GEORGE J. PAULY.
